PUMPMOBILE TOY

Carl Alfred Swenson and Philip R. Swenson,
Loves Park, Ill.

Application June 3, 1950, Serial No. 165,956

8 Claims. (Cl. 46—107)

1

This invention relates generally to a wheeled top vehicle and more particularly to that type of child's vehicle which is propelled forwardly by the pumping action of a handle bar operated by a seated rider, the vehicle being steered by the rider's feet resting on opposite ends of the front axle.

The general object of the invention is to provide a power actuated toy vehicle of the above character which has an articulated figure thereon and in which the motions of the body, arms, and legs of the figure closely simulate the natural motions of a child operating such a vehicle.

Another object is to simulate the leg motions of a child steering a vehicle of the above character by connecting the feet of the figure to the front axle and oscillating the latter in a novel manner during propulsion of the toy.

A further object is to mount the front axle on the vehicle in a novel manner for selectively varying the path travelled by the latter.

The invention also resides in the novel manner of oscillating the front axle and the handle bar of the vehicle to prevent damage to these parts by too rapid actuation thereof.

Other objects and advantages of the invention will become apparent from the following detailed description taken in connection with the accompanying drawings, in which

Figure 1 is a perspective view of a wheeled toy vehicle embodying the novel features of the present invention.

Fig. 2 is a fragmentary sectional view taken along the line 2—2 of Fig. 3 with some of the parts broken away.

Fig. 3 is a fragmentary sectional view taken along the line 3—3 of Fig. 2.

Fig. 4 is a fragmentary view similar to Fig. 3 showing the parts in a different position.

Fig. 5 is a plan view of the motor.

Fig. 6 is a fragmentary perspective view.

While the invention is susceptible of various modifications and alternative constructions, I have shown in the drawings and will herein describe in detail the preferred embodiment. It is to be understood, however, that I do not intend to limit the invention by such disclosure but aim to cover all modifications and alternative constructions falling within the spirit and scope of the invention as expressed in the appended claims.

The toy vehicle shown for purposes of illustration includes an elongated box-like frame having a wheeled support and comprising upright

2

sheet metal side and end walls 10 and 11 integral with a bottom wall 12 and connected as by bent over lugs to a top wall 13. In this instance, the wheeled support includes horizontal front and rear axles 14 and 15 projecting transversely of the frame at opposite ends of the latter and having front wheels 16 and 17 and rear wheels 18 and 19 thereon engageable with a supporting surface for the vehicle. Intermediate the ends 10 of the frame, an upright handle 20 in the form of a lever having a cross bar 21 at its upper end is fulcrumed adjacent its lower end on a horizontal shaft 22 spanning the side walls 10. The handle projects upwardly from the shaft through a slot 23 formed in the top wall of the frame to permit the handle to rock back and forth about the shaft.

A figure 24 which is mounted on the frame top wall 13 behind the handle 20 comprises a body portion 25 having stiff arms 26 and jointed legs 27 pivoted adjacent their inner ends to upper and lower parts of the body. Herein, the latter is secured to a seat 28 pivoted on ears 29 bent up from the frame top wall and the arms, 25 at their outer ends, are pivotally connected to the bar 21 of the upright handle 20. Thus, during oscillation of the latter, the body of the figure is rocked through the medium of the arms back and forth longitudinally of the frame.

To simulate closely the natural motions of a child steering a pumping type of vehicle, the feet 30 of the jointed legs 27 of the child's figure are pivotally connected at spaced points to the front axle 14 and the latter is mounted on the frame to rock about an upright axis. Such rocking is permitted by cutting away the frame side walls 10 adjacent their forward ends as indicated at 31 (Fig. 1). In this instance, the front axle is pivotally supported by an L-shaped member 32 mounted on the frame and having one leg 33 upstanding along the right side wall of the latter and formed with a hole 34 to receive the axle. A washer 35 pressed on the axle limits axial movement thereof in one direction relative to the upstanding pivot leg while movement in the opposite direction is limited by crimping the axle as indicated at 36.

The present invention contemplates utilizing the power applied to the vehicle for propelling the same as by a motor 38 to rock the handle 20 about the shaft 22, rock the figure 24 back and forth, flex the jointed legs 27, and steer the vehicle all to simulate the natural motion of a child operating such a vehicle. In the present 55 instance, the motor comprises a spiral spring

39 having one end anchored to the frame and the other end connected to a horizontal shaft 40 which is journaled in spaced parallel plates 41 of a gear box 42 secured as by a screw 43 to the frame bottom wall 12 at the rear portion thereof. The shaft 40 may be turned to wind up the spring by a key 44 coupled to a projecting end of the shaft. A spur gear 45 fast on the latter meshes with a pinion 46 journaled on an intermediate shaft 47 and secured to a spur gear 48 which meshes with a hollow long pinion 49. The latter is journaled in the gear box plates 41 and has a driving connection with the rear axle 15 to propel the vehicle.

To facilitate assembly of the motor 38 and the rear axle 15 and prevent damage to the parts of the toy by too rapid actuation thereof when the toy is raised from the supporting surfaces, the invention contemplates connecting the motor to only one rear wheel 18 and actuating the front axle 14 and the handle 20 by motion derived from the other rear wheel 19 which is rotatable relative to the driving wheel 18. This is accomplished in the present instance by securing the rear wheels to the outer ends of the rear axle 15 and forming the latter in two relatively rotatable sections 51 and 52 one of which is driven by the motor and the loose one of which has a driving connection with the front axle and the handle. To connect the motor to the driving axle section 51, the long hollow pinion 49 at one end is secured to and supports the inner end of the section. At its other end, the pinion rotatably receives and provides a supporting bearing for the inner end of the loose axle section 52. By making the pinion of substantial length as shown, the axle sections may project outwardly through enlarged holes in the side walls 10 of the frame and require no outboard bearing support. Axial movement of the pinion in opposite directions relative to the gear box is limited by a washer 53 secured to the pinion and a gear 54 fast on the driving axle section 51 outside of the gear box. This gear is connected to suitable governing mechanism (not shown) for controlling the speed at which the driving wheel rotates.

The rotary motion of the loose axle section 52 and the wheel 19 thereon is utilized to actuate the handle 20 and the front axle 14 through the provision of a reciprocating member or slide 55 having pivotal connections with these parts and reciprocated longitudinally of the frame by a crank 56 which is rotatable in unison with the loose axle section. Herein, the crank is a spur gear having an eccentric pin 57 thereon and secured to a shaft 58 journaled in the spaced plates 41. Meshing with the crank is a pinion 59 fast on the loose axle section and forming a speed reducing connection between the latter and the crank so that the parts of the figure are actuated slowly to resemble the slow pumping and steering actions of a child operating the above described type of vehicle. Movement of the loose section axially in opposite directions is limited by engagement of the pinion 59 fast thereon with the long pinion 49 and the left side wall 10.

In this instance, the slide 55 is generally L-shaped in cross section having an upright leg 60 disposed alongside the left one of the frame side walls 10 and formed with a vertical slot 61 in its rear portion to receive the eccentric pin 57 and connect the crank 56 to the slide for reciprocation of the latter in the rotation of the crank. At its forward end, the upright slide leg is pivot-

ally connected to the front axle 14 by a downwardly opening slot 62 formed in the leg and receiving the axle at a point spaced along the latter from the swivel axis therefor. The other leg 63 of the slide is disposed horizontally under the frame top wall 13 and is formed with a slot 64 adapted to receive the handle 20 and pivotally connect the latter to the slide. Thus, the slide, in addition to rocking the front axle about its swivel axis, also oscillates the handle to rock the figure 24 back and forth longitudinally of the frame.

The path to be travelled by the toy vehicle may be changed selectively by moving the swivel axis of the front axle 14 longitudinally of the frame in a novel manner so as to vary the inclination of the mean position of oscillation of the axle relative to the longitudinal axis of the frame. In this instance, such movement of the swivel axis is effected simply by disposing the other leg 65 of the L-shaped member 32 horizontally and pivotally connecting the same as by a rivet 66 to the frame bottom wall 12. To facilitate swinging of the pivot leg 33, an extension 67 thereof may be projected upwardly through an arcuate slot 68 in the top wall 13 as shown, movement of the L-shaped member in opposite directions about the rivet 66 being limited by engagement of the horizontal leg 65 with the left side wall 10 as shown in Figs. 3 and 4.

Assuming that the toy is being propelled forwardly by the spring 39 acting through the driving axle section 51, the motion of the loose wheel 19 in rolling along the supporting surface, is converted to reciprocatory motion of the slide to rock the handle 20 and the figure 24 slowly back and forth longitudinally of the frame. Such oscillation of the figure is between the rearmost position shown in Fig. 2 in which the body 25 is upright and a forward position shown in Fig. 1 in which the body is inclined forwardly.

During such forward motion of the vehicle, the slide also swings the left portion of the front axle 14 about the pivot leg 33 back and forth between the positions shown in full and in phantom in Fig. 3 in which the pivot leg is shown in its most forward position. In the position of the axle shown in full, the front wheels are turned to the left and the axle is inclined with respect to the longitudinal axis of the frame. In the position shown in phantom, the wheels are only slightly turned to the left and the axle is almost normal to the longitudinal axis of the frame. Thus, during propulsion of the vehicle, the mean position of the front axle is such that the toy travels in a large circle to the left.

To change the path travelled by the toy, the pivot leg 33 is merely swung clockwise about the rivet 66 from the position shown in Fig. 3 to move the swiveling axis rearwardly and thereby vary the inclination of the front axle relative to the longitudinal axis of the frame for the position of the slide shown in Figs. 3 and 4. With the pivot member in the position shown in Fig. 4, the axle is oscillated between the position shown in full in this figure in which the wheels point nearly straight ahead and the position shown in phantom in which the wheels are turned to the right. Thus, the inclination of the mean position of oscillation of the axle is such that the right front wheel is back of the left wheel and the toy moves around a circle to the right.

From the foregoing, it will be apparent that, during the oscillation of the front axle, the jointed legs 27 of the figure 24 are flexed in the same

manner as a child steering a vehicle of the character described and the body 25 and arms 26 go through the same motions as a child pumping the handle of such a vehicle. Since the spring 39 acts through only the driving wheel 18 and the movable parts of the figure are actuated by rotation of the loose wheel 19 only, free running of driving wheel when the latter is not held against rotation will be ineffectual to move the figure or cause excessive vibration of the same. Thus, the life of the toy is prolonged. By using the L-shaped member 32 to define the swiveling pivot of the front axle and by using the slide 55 to actuate both the latter and the handle, the construction of the toy is greatly simplified.

We claim as our invention:

1. A toy vehicle having, in combination, a frame, a power driven motor on the frame for propelling the vehicle, a wheeled support for said frame including a horizontal front axle mounted on the frame to oscillate about an upright swivel axis, an upright handle pivoted on said frame intermediate the ends of the latter to swing back and forth longitudinally of the frame, a figure having its body pivoted on said frame and having swingable arms pivotally connected to said handle, said figure having jointed legs with feet pivotally connected to said axle at points spaced along the latter, a member reciprocable longitudinally of said frame, means pivotally connecting said member to said handle and operable to swing the latter forwardly and backwardly and rock said figure through the medium of said arms during reciprocation of the member, means pivotally connecting said member to said axle at a point spaced from said axis to oscillate the axle and thereby flex said legs during reciprocation of the member, and mechanism on said frame operable during forward movement of said vehicle to reciprocate said member.

2. A toy vehicle having, in combination, a frame having front and rear wheels, a motor on said frame for propelling the vehicle, a wheeled support for said frame including a horizontal front axle, an L-shaped member having an upright leg pivotally supporting said axle for swiveling of the latter about an upright axis, a slide mounted on said frame for movement longitudinally thereof and having a pivotal connection with said axle spaced along the latter from said axis, mechanism on said frame operable during forward movement of said vehicle to reciprocate said slide forwardly and backwardly and thereby oscillate said axle about said axis, and a connection between the other leg of said member and said frame pivotally supporting the member for selective bodily adjustment of said upright axis longitudinally of said frame to vary the inclination of the mean position of oscillation of said axle relative to the longitudinal axis of said frame.

3. A toy vehicle having, in combination a frame, a motor on said frame for propelling the vehicle, a wheeled support for said frame including a horizontal front axle, means defining a pivot for said axle for swiveling of the latter about an upright axis, a member movable longitudinally of said frame and having a connection with said axle spaced along the latter from said pivot therefor, mechanism on said frame operable during forward movement of the vehicle to reciprocate said member back and forth and thereby oscillate said axle about said axis to steer the vehicle, and means mounting said pivot means on said frame for selective bodily adjust-

ment of said axis longitudinally of the frame to vary the inclination of said axle relative to the longitudinal axis of the frame for a given position of said member.

4. A toy vehicle having, in combination, a frame, a power driven motor mounted on the frame and operable to propel the vehicle, a wheeled support for said frame including a horizontal front axle mounted on the frame to oscillate about an upright axis, a figure mounted on said frame intermediate the ends thereof and having jointed legs with feet pivotally connected to said axle at points spaced along the latter, a slide mounted on said frame to reciprocate back and forth longitudinally thereof and pivotally connected to said axle at a point spaced from said swivel axis, and mechanism operable during propulsion of the vehicle to reciprocate said slide and oscillate said axle to flex said legs and thereby simulate the motions of a child steering a vehicle.

5. A toy vehicle having, in combination, a frame, a wheeled support for said frame including a rear axle having a driving section and a loose section axially aligned and mounted on the rear portion of said frame to rotate relative to each other, a rear wheel fast on the outer end portion of each of said axle sections and engageable with a supporting surface, a power driven motor on said frame, mechanism operatively connecting said motor to said driving axle section to propel the vehicle, a figure mounted on said frame and having parts movable relative thereto, and mechanism operatively connecting said movable figure parts and said loose axle section and operable during propulsion of the vehicle to change the rotary motion of the axle section to oscillatory motion of the figure parts.

6. A toy vehicle having, in combination, a frame, a wheeled support for said frame including a driving wheel and a loose wheel supporting the rear end of the frame, a power driven motor on said frame operatively connected to said driving wheel to propel the vehicle, a horizontal front axle mounted on the frame to swivel about an upright axis, a figure on said frame having jointed legs with feet pivotally connected to said axle at points spaced along the latter, and mechanism on said frame operatively connecting said loose wheel and said axle and operable automatically during propulsion of the vehicle to change the rotary motion of the loose wheel to oscillating motion of the axle about said upright axis and thereby flex said legs.

7. A toy vehicle having, in combination, a frame, a wheeled support for said frame including a loose wheel and a driving wheel supporting the rear end of the frame, a motor on said frame operatively connected to said driving wheel to propel the vehicle, an upright handle pivotally connected to said frame, a figure pivotally mounted on said frame and movable with said handle to simulate a pumping action, a rotary member on the frame, a speed reducing connection between said loose wheel and said member for rotating the latter in unison with the wheel, and mechanism for converting the rotary motion of said member into oscillatory motion of said handle and said figure.

8. A toy vehicle having, in combination, a frame, a wheeled support for said frame including a driving wheel and a loose wheel supporting the rear end of the frame, a power driven motor on said frame operatively connected to said driving wheel to propel the vehicle, a figure

mounted on said frame and having parts movable relative to the latter, and mechanism on said frame operatively connecting said loose wheel and said movable parts of said figure and operable during propulsion of the vehicle to change the rotary motion of the loose wheel to oscillating motion of the figure parts.
